UNITED STATES PATENT OFFICE.

CHARLES T. NELSON, OF OAKLAND, NEBRASKA.

AUTOMOBILE-JACK.

1,224,561.

Specification of Letters Patent.

Patented May 1, 1917.

Application filed October 4, 1916. Serial No. 123,749.

To all whom it may concern:

Be it known that I, CHARLES T. NELSON, a citizen of the United States, residing at Oakland, in the county of Burt and State 5 of Nebraska, have invented certain new and useful Improvements in Automobile-Jacks; and I do hereby declare the following to be a full, clear, and exact description of the invention, such as will enable others skilled in 10 the art to which it appertains to make and use the same.

This invention relates to improvements in automobile jacks.

The object of this invention is to provide 15 a jack which is particularly adapted for use in connection with motor vehicles and the like, and is designed to provide a device whereby the vehicle may be readily run over the same and lift it from the ground so that 20 the tires clear the ground thereby relieving them of any unnecessary strain and preventing them from coming in contact with the surface of the ground when not in use.

Another object of this invention is to provide 25 a device which will simultaneously lift the machine or the vehicle and hold the same against accidental movement.

A still further object of this invention is to provide a novel form of lifting means 30 and also to provide a pair of supporting bars which may be readily inserted under a machine so that the same may be quickly and readily raised with a minimum expenditure of energy.

With these and other objects in view the invention consists in the novel combination and arrangement of parts hereinafter more 35 fully described and pointed out in the claims hereto appended.

40 In the drawing

Figure 1 is a perspective view of my improved jack including the windlass for raising the same.

Fig. 2 is a detail sectional view.

45 Like numerals of reference designate corresponding parts in all the figures of the drawing.

Referring more particularly to the drawing, the numeral 1 designates one of the base 50 members of the device while the numeral 2 designates the coöperating base member. The base members are preferably formed of wood or any other suitable material and so constructed as to lie even and firm upon the 55 ground and to provide a frame of suitable construction for supporting the jack struc-

ture which will be hereinafter more fully described.

The members 1 and 2 are arranged at a relatively spaced distance apart and have 60 rotatably mounted near each of their ends shafts 3 and 4, which are designed to support the supporting arms 5. The shafts are held to the base members 1 and 2 by suitable staples 6 which permit the free rotation of 65 the shafts which rotation will be hereinafter more fully set forth.

Secured to the shafts 3 and 4 near their ends and within the space between the base members 1 and 2 are the lifting arms 5, each 70 of which comprises at their lower end a sleeve member 7 which is rotatably mounted on the shafts 3 and 4. The mounting of the sleeves around the shafts acts as a support for the arms 5. The upper ends of the arms 75 5 are bifurcated to provide supporting arms 8.

Pivotedly mounted in the arms 8 are the longitudinally extending supporting bars 9 which bars have each of their ends fitted in 80 the slot defined by the arms 8 to rest upon the bottom wall of the slot formed by the bifurcating of the arms 5. The arms 8 of each of the members 5 are provided with alining transversely arranged openings 10 85 through which is adapted to extend the reinforcing bars 11.

The reinforcing bars 11 are substantially V-shaped and have their apexes slidably mounted through the eyes 12 of bolts 13 90 which are removably secured to the shafts 3 and 4 intermediate the ends thereof. The opposite ends of the members 11 are bent angularly in a horizontal direction and are removably extended through openings 10 in 95 the arms 8 and the bars 9 permitting the bars to move downwardly and upwardly upon the movement of the arms 5.

A bail member 13' has each of its ends rigidly secured to the forward lifting elements 5 and this bail is arranged to provide a means by which the simultaneous operation of all the lifting arms is obtained.

The lifting mechanism used in connection with this jack comprises a suitable support, designated generally by the numeral 15, which may be a wall of a building or other suitable structure, but as illustrated comprises a pair of vertical bars 14, which are set into the ground and connected near 105 the point where they enter the ground by plates 16', which are provided with apertures 110

therein near each end, through which the bars 14 extend. Pivotaly mounted between the bars 14 at a point intermediate the ground and their upper ends is a suitable bail 16, the use of which will be more fully hereinafter described. Rotatable between the bars near their upper ends is a shaft 17 carrying thereon the winding drum 18. This shaft is provided at one end with a gear wheel 19 and at its opposite end with a suitable ratchet wheel 20, which is designed to coöperate with a pawl 21 to hold the shaft and drum against rotation in one direction. A suitable flexible member 22 is connected 10 at one end to the drum 18, and passes over one of the pulleys of the double block 23, which has a hook 24 which engages the bight portion of the bail 13'.

The opposite end of the flexible member 20 is passed through the block 25 and extended again through the block 23 and has its end connected to a hook 26 carried by the block 25. A suitable hook 27 is also carried by the block 25 and is designed for engagement 25 with the bight portion of the bail 16, so that a connection is established between the bails 16 and 13'.

In operation it will be apparent that the car or vehicle which is to be lifted is run up 30 over the platform or bars 9 so that the bars will engage the forward and rear axles.

The wheel 19 is then set in operation to wind the flexible member 22 on the drum 18, this action causing the blocks 23 and 25 to 35 be drawn toward each other, thereby exerting pull on the bails 13' and 16, causing the lifting elements 5 to move to a vertical position.

It is apparent that when the lifting elements 40 are in a vertical position the vehicle axles will rest thereon and the wheel will be held clear of the ground, thus relieving the tires of the weight of the vehicle and

also permitting any repairs to be made to the wheels which might be necessary. 45

What is claimed is:—

1. A jack of the class described including a base, a pair of shafts rotatably mounted on the upper side of the base near each end thereof, lifting elements secured by one end 50 to the shafts at each end thereof for rotation therewith, the upper ends of said lifting elements being bifurcated forming spaced arms provided with horizontally alined openings, a pair of V-shaped reinforcing 55 rods having their apexes removably secured to the medial portion of each shaft, the ends of the reinforcing rods being bent angularly and extended transversely through the horizontal alined openings in the arms of the 60 lifting elements, longitudinally extended supporting bars arranged between the arms of the lifting elements and removably and pivotally secured therein by the angularly bent ends of the V-shaped reinforcing rod, 65 and a power applying mechanism associated with certain of said lifting elements for raising and lowering the lifting elements and bars simultaneously.

2. A jack of the class described including 70 a base, a pair of shafts rotatably mounted on the base, lifting elements secured by one end to the shaft for rotation therewith, reinforcing rods secured to each shaft, the ends of the reinforcing rods passing through the 75 upper end of the lifting elements, supporting bars removably and pivotally secured to the ends of the reinforcing rods, for movement with the lifting elements.

In testimony whereof I affix my signature 80 in presence of two witnesses.

CHARLES T. NELSON.
